UNITED STATES PATENT OFFICE.

HENRY C. MABIE, OF MAYWOOD, NEW JERSEY.

CLIP FOR FOUNTAIN-PENS, PENCILS, AND THE LIKE.

1,061,193.

Specification of Letters Patent.

Patented May 6, 1913.

Application filed November 19, 1912. Serial No. 732,263.

To all whom it may concern:

Be it known that I, HENRY C. MABIE, a citizen of the United States, and a resident of Maywood, in the county of Bergen and 5 State of New Jersey, have invented certain new and useful Improvements in Clips for Fountain-Pens, Pencils, and the Like, of which the following is a full and clear specification.

10 My invention relates to the construction and mounting of clips used in connection with fountain pens, pencils and similar articles for detachably securing them to the pocket of the wearer. It has already been 15 proposed to form such clips of resilient sheet metal, wire and the like, bent into such form as to provide a yielding engagement of the retaining finger with the cloth of the pockets which slides into engagement between the 20 retaining finger and the body of the pen or the like. These members have been secured to the pen or the like in various ways such as by external spring bands and by integral tongues or separate rivets which pass through 25 perforations in the shell wall of the pen or the like.

The present improvements are in that type of holder or clip in which the retaining finger is secured in place by a member which 30 passes through the perforated shell wall of the pen or the like.

It may be stated here that the invention is applicable to fountain pens, pencils and other articles to be carried in the pocket, but 35 to illustrate the same I shall refer to an embodiment thereof employed in connection with an adjustable feed pencil, which it will be understood, comprises a tubular shell or casing forming the main body of the pencil, 40 a lead or other marking member longitudinally disposing therein and a feed mechanism for the marking member by which the marking member is projected for use and may be withdrawn into the shell if desired, 45 when not in use.

The objects of my invention are mainly to improve the operation of the clip in securing the article to the pocket and to so secure the clip to the article that it shall be practically 50 rigid and cannot become disengaged by wear or use.

The invention is illustrated in the accompanying drawing, in which—

55 Figure 1 is a side elevation of a pocket pencil with the clip attached. Fig. 2 is a front elevation of the blank from which

the clip is formed. Fig. 3 is a sectional side elevation of a portion of the pencil shell and the clip secured thereto. Fig. 4 is a front elevation of a slightly modified form 60 of blank from which the clip may be made, and Fig. 5 is a sectional side elevation showing a portion of the pencil shell with the modified form of clip applied thereto.

Referring now more specifically to said drawings 10 indicates the pencil shell, 11 the marking member and 12 the feed operating member therefor. The clip is shown as comprising the resilient retaining finger 13 of ordinary configuration, base or bearing 70 portion 14, which rests firmly against the surface of the pencil shell 10, and the attaching or securing tongue 15. As shown in Fig. 2, the blank from which the clip is made is formed with the securing tongue 15 of 75 less width than the bearing surface of base portion 14 which latter is perforated at 16 and preferably countersunk at 17. The perforation 16 and countersink 17 correspond in dimensions with the securing tongue 15 80 so that the latter can be passed through the perforation 16 and bent over and seated in the countersink 17, in attaching the clip to the shell. This operation is illustrated in Fig. 3 in which the shell 10 is shown as having upper and lower perforations through which the tongue 15 is passed first through the upper perforation and then after being bent downward through the lower perforation of the shell and out through the perforation 16 of the base portion of the clip. 85 The end of the tongue is then bent upwardly into the countersink 17, where it is permanently retained. It will be seen that this construction provides for the clip being secured to the shell by points of attachment which are spaced apart substantially the full length of the base portion, thus insuring a 90 high degree of firmness, and in addition to this feature that the base portion 14 and tongue 15 pass entirely around a portion of the metal of the shell 10 and are locked together by the engagement of the end of the tongue with the base portion in the countersink 17, so that the clip cannot become disengaged from the shell, due to use and wear. 95

In the modification shown in Figs. 4 and 5, the construction and arrangement is in most of its parts substantially the same as that above illustrated and described. In this 100 form, however, shell 10 has secured to it a clip comprising a retaining finger 18, a bear-

ing surface or base portion 19, perforated at 20 without countersink, and a securing tongue 21 which passes through upper and lower perforations in the shell 10 in the same manner as above described but which, upon being brought out through the perforation 20 in the base portion 19 of the clip, is turned upwardly and forced down flat against the outer surface of base portion 19. The effect 10 in either form is substantially the same with the possible exceptions in favor of the form illustrated in Figs. 1, 2 and 3, that the engagement of the end of tongue 15 with the base portion is more snug with the countersink and hence more secure and the end of the tongue is protected better against becoming dislodged.

I claim:

1. A clip of the character described comprising in combination a base portion with a perforation near one end thereof, a retaining finger, and an attachment tongue projecting from the end of said base portion which is remote from the perforation, corresponding in width with said perforation and of greater length than the distance from said perforation to said remote end of base portion.

2. A clip of the character described, comprising in combination a perforated base portion, a retaining finger integral with and projecting longitudinally from one end of said base portion and an attachment tongue integral with and projecting from the other end of said base portion, said attachment tongue being of a width corresponding with the width of said perforation in the base portion and of a length greater than the distance from its junction with said base portion to said perforation in the base portion.

3. A clip of the character described, comprising in combination a perforated base portion having a countersink adjacent thereto, a retaining finger integral with and projecting longitudinally from one end of said base portion, and an attachment tongue integral with and projecting longitudinally from the other end of said base portion, said tongue being of a width corresponding with the said perforation and countersink in the base portion and of a length greater than the distance from its junction with said base por-

tion to said perforation plus the length of said countersink.

4. A clip of the character described, comprising in combination a base portion having a perforation near one end thereof, a retaining finger integral with and projecting longitudinally from the perforated end of said base portion and an attachment tongue integral with and projecting from the other end of said base portion, said tongue being of a width corresponding with said perforation in the base portion and of a length greater than the distance from its junction with the base portion to said perforation.

5. A device of the character described, comprising in combination a tubular shell having perforations therein longitudinally spaced apart and a clip comprising a base portion of a length commensurate with the distance between said perforations in the shell and having a perforation near one end adapted to register with one of said shell perforations, a yielding retaining finger projecting longitudinally from the perforated end of said base portion and an attachment tongue projecting longitudinally from the other end of said base portion, said tongue passing inwardly through one of said shell perforations and outwardly through the other shell perforation and the registering perforation in the base member and folded over against the outer surface of said base member to retain the clip in position.

6. A device of the character described, comprising in combination a tubular shell having perforations longitudinally spaced apart therein, and a clip having a base portion with a perforation and countersink near one end, a yielding retaining finger projecting longitudinally from the perforated end of said base portion, and an attachment finger projecting from the other end of said base portion and passing inwardly through one of said shell perforations and outwardly through the other shell perforation and said base perforation with its end bent over and seated in said countersink.

HENRY C. MABIE.
